UNITED STATES PATENT OFFICE.

CALVIN C. FOUTS, OF MIDDLETOWN, OHIO, ASSIGNOR TO THE ARKANSAS CORRUGATED METAL CULVERT COMPANY, OF LITTLE ROCK, ARKANSAS.

GUTTER-BRIDGE.

979,754.

Specification of Letters Patent. Patented Dec. 27, 1910.

Application filed April 10, 1908. Serial No. 426,209.

To all whom it may concern:

Be it known that I, CALVIN C. FOUTS, a citizen of the United States, residing at Middletown, Butler county, Ohio, have invented certain new and useful Improvements in Gutter-Bridges, of which the following is a specification.

My improved gutter-bridge will be readily understood from the following description taken in connection with the accompanying drawing in which:

Figure 1 is a vertical transverse section of the bridge: Fig. 2 a vertical longitudinal section of the same: and Fig. 3 a perspective view of one corner of the bridge.

In the drawing:—1, indicates the lower or chord member of the bridge, shown in the form of a flat plate: 2, the upwardly and inwardly turned side-edges of the chord member forming retaining lips: 3, an arch of corrugated metal with its ends engaging under the lips of the chord member, the corrugations of the arch extending from lip to lip: 4, arch or other material supported by the bridge: and 5, the opening through the bridge between the chord and arch.

The length of the structure is to be in accordance with the width of the walk to be supported by the bridge, and, in addition, to serving as a mere bridge, the length may be prolonged to any extent desired to form a sewer conduit. Such conduits of considerable length may be formed of comparatively short sections connected together at their ends, as by riveting, though the form is such that for buried conduits no riveting is essential, it being sufficient to let the end of one section enter the end of the succeeding section, the corrugations causing the sections to lock together sufficiently for all practical purposes.

It will be observed that this structure, considered as a gutter-bridge or as a conduit, calls for no extra fastenings, that is to say, the arch may be shipped in flat form, or in curved forms nested together and later assembled with the comparatively flat chords which may be shipped in flat form. Again, the absence of rivets or the like connecting the arch with the chord renders possible the endwise connection of two of the sections with great facility it being only

necessary to lay the chord end to end and then, after the contiguous ends of the two arches have been placed in overlapping relation, spring both of the arches inward to enter between the lips of the chords, both arches then expanding to engage under the lips. It is to be further observed that the side edges of the arch-member are left in their natural condition, or unflanged, and that the upturning of the lips of the base-member are at such an angle to the base-member that the side edges of the arch will catch under them and be securely held without the necessity for any flanging of the arch, and the construction is such that the parts will go together satisfactorily even in case of such bending and denting as is apt to occur in loosely shipped sheet metal parts of this general character.

I claim:

1. A gutter bridge or conduit comprising, a sheet-metal chord-member provided at its side edges with lips turned upwardly and at an angle inwardly from the vertical, and a transversely corrugated sheet-metal arch-member having its corrugated side edges engaging under said angular lips, combined substantially as set forth.

2. A sheet metal pipe including a longitudinally flat section and an annularly corrugated opposite section with overlapping edges, the edges of the flat section being crimped to fit the opposite section, combined substantially as set forth.

3. A sheet metal pipe including a flat chord section having edges bent to form an angle and a corrugated arch-section having its edges abutted into the angles formed by the edges of the chord section, the edges of the chord section being shaped to fit engaging portions of the arch-section.

4. A sheet metal pipe including a flat section and an annularly corrugated opposite section, with overlapping edges.

5. A sheet metal pipe including a flat and an annularly corrugated opposite section joined together at the edges.

6. A sheet metal pipe including a flat section and an annularly corrugated opposite section, the edges of one section being flanged and the edges of the other section being abutted in the angles of the flanges.

7. A sheet metal pipe including a flat sec-

tion and an annularly corrugated opposite section with overlapping edges, the edges of one section being shaped to fit the other section.

- 5 8. A metal culvert pipe having a flat bottom with upturned side edges, a semi-cylindrical top adapted to engage said bottom,

said side flanges arranged to overlap the lower portions of said top.

CALVIN C. FOUTS.
